by Mr. E. Valdett, Atty.

UNITED STATES PATENT OFFICE.

LEWIS MOORE, OF JOLIET, ILLINOIS, ASSIGNOR TO MOORE BROTHERS COMPANY, OF JOLIET, ILLINOIS, A CORPORATION OF ILLINOIS.

STOVE.

939,529.

Specification of Letters Patent.

Patented Nov. 9, 1909.

Application filed May 12, 1909. Serial No. 485,442.

To all whom it may concern:

Be it known that I, LEWIS MOORE, a citizen of the United States, and a resident of Joliet, in the county of Will and State of Illinois, have invented certain new and useful Improvements in Stoves, of which the following is a specification.

This invention relates to stoves and ranges and relates particularly to oven doors therefor of the type comprising a glass window or panel through which the contents of the oven can be inspected.

While attempts have heretofore been made to construct oven doors of this type, so far as I am aware, in such former attempts large single panes or plates of thick, heavy glass have been used and have all resulted unsuccessfully, due to warping or distortion of the panes in manufacture, whereby internal stresses are developed therein when said panes are secured in the rigid frames formed in the oven doors to receive them, and to the excessive expansion and contraction of said panes in use, arising from the high degree 25 of heat in wide range of temperature to which they are subjected, which causes, particularly, when coöperating, soon result in the breaking of said panes.

The primary object of the present invention is to overcome this very objectionable feature, which I have discovered can be done in a simple and effective manner by the use of windows comprising a plurality of small panes of glass, which are distorted 35 very little, if at all, in manufacture and which expand and contract independently, so that each pane will be unaffected by the expansion and contraction of the other panes. In this manner the internal stresses 40 developed in said panes are too slight to break the glass.

A further object of the invention is to provide a simple framework for connecting the adjacent edges of the different panes, 45 which will hold said panes loosely, thus permitting the use of panes aggregating less in width than the width of the continuous frame opening in the door in which they are secured, thereby providing for free expansion and contraction of said panes, said frame members being so constructed, also, that they will close any spaces which might

otherwise be formed between the adjacent edges of the different panes.

A further feature of the invention relates 55 particularly to oven doors which are pivoted at their lower edges and are adapted to form shelves for supporting utensils and dishes when placing them into and withdrawing them from the stove ovens. As my invention relates to this feature, the object of the invention is to provide bearing surfaces or skids which extend slightly above the inner surfaces of the window panes, which will sustain the weight of the utensils and dishes 60 resting on the doors above the windows therein and on which the utensils or dishes may be slid into and out of the oven without coming into direct contact with the glass, thus insuring against scratching and mar- 65 ring of the glass.

To effect these several objects my invention consists of the various features and details of construction hereinafter described and claimed.

In the accompanying drawing, in which my invention is fully illustrated—Figure 1 is a front view of the outside of an oven door embodying my invention. Fig. 2 is a partial view of the inner side thereof, part 75 of the lining plate being broken away to expose parts covered thereby. Fig. 3 is an enlarged sectional view on the line 3—3 of Fig. 1. Fig. 4 is an enlarged sectional view on the line 4—4 of Fig. 1. Fig. 5 is an enlarged sectional view on the line 5—5 of Fig. 1; and Fig. 6 is a longitudinal sectional view of one of the frame members which connect the edges of adjacent panes or plates 80 of glass.

Referring now to the drawings, A designates, as a whole, an oven door which, as regards its general features, is of familiar construction, comprising the door proper 1, commonly made of cast iron recessed at its 95 rear side, and a lining 2, commonly made of sheet steel or the like, adapted to close the rear side of the recess in said door proper, thus forming a dead air space in said door. The position of said lining is defined by lugs 3 on the door proper 1 on which said lining rests, and said lining is secured to the door proper by bolts 4, said lugs 3 preferably comprising lugs located closely

adjacent to the bolts 4 and to the edges of the recess in the rear side of said door proper. As shown, also, said door is of the type the lower edge of which is adapted to be pivotally connected to the body portion of the stove so that it may be turned outwardly and downwardly into horizontal position to form a shelf for supporting utensils and dishes when being inserted into and withdrawn from the oven. To provide for thus supporting said door A it is provided at its lower corners with lugs 5, adapted to engage corresponding bearings, not shown, on the body portion of the stove, in a familiar manner.

Formed in the door A and comprising corresponding openings in the door proper 1 and in the lining 2, is a continuous opening 6 which is closed by a window comprising two or more separate panes or plates of glass 7, a desirable size for said panes or plates 7 being about 8 inches long by 5 inches wide. To effect the objects of my invention as it relates to relieving the panes or plates of glass 7 from all stresses due to distortion or warping of said panes or plates in manufacture and expansion and contraction thereof in use, incident to securing the same rigidly in the opening 6, I secure said panes or plates 7 in position in the following manner:—Formed around the opening 6 in the door proper 1 is a rabbet 8 which is adapted to receive the panes or plates of glass 7, said panes or plates of glass being secured in said rabbet by the overlapping edges of the lining 2 when secured to the door proper 1, the edges of said lining around the hole or opening therein being preferably bent down slightly to form a short lip 9, the relation being such that when said lining is secured in position, there will be a slight clearance between the end of said lip and the surface of the panes or plates of glass, see particularly Fig. 4. The adjacent edges of the panes or plates 7 are confined in grooves 10 formed in frame members 11, which extend across the opening 6 in the door A, the ends of which are secured in the rabbet 8 of the lining 2 at opposite sides of said opening 6, the thickness of said frame members being such, however, that the ends thereof will be firmly clamped in said rabbet 8 by the lining 2, see particularly Fig. 5, thus permitting only very limited movement of the plates or panes 7. The grooves 10 are made slightly wider than the thickness of the panes or plates 7 and the webs 12 of said frame members are made sufficiently strong and rigid to prevent compression thereof under their designed conditions of use, thus insuring that the sides of the grooves 10 will not be rigidly clamped upon the edges of said panes or plates. To provide a tight joint between the sides of the grooves or channels 10 and the plates or

panes of glass 7 and to prevent rattling of said plates or panes in the grooves 10, the sides of the grooves 10 are preferably compressed together slightly at their outer ends, so that they will have slight frictional engagement with the sides of said plates or panes, the sides of said grooves being made sufficiently thin, however, to render them easily expansible.

The frame members 11, in which are formed the grooves 10 which receive adjacent edges of adjacent panes or plates 7, are preferably connected together to form in effect a unitary structure. Said frame members will thus operate to confine said panes or plates and to limit the movement thereof as desired and will also operate to connect adjacent panes or plates and to form a practically tight joint between them.

As shown, the frame members 11 are formed of thin sheet metal bent to form the grooves or channels 10, two sections of which of proper length are preferably secured together with their web sections in contact, which may be done in any desired manner. As shown, each pair of frame members 11 is formed from a single piece of suitable sheet metal of sufficient length to form two single frame members, the edges thereof being bent to form a continuous groove 10. The sides of said groove are then severed at the middle of said piece or strip and the web portion bent back upon itself to bring the webs of different sections into contact and the outer ends thereof secured together, as by a tongue 13 forming an extension at the free end of the web of one of said sections which is bent over the web of the other section, all as clearly shown in Fig. 6 of the drawing.

Suitable packing, as strips 14 of asbestos, are preferably inserted in the rabbet 8 to provide a tight joint around the edges of said window. Beneath the ends of the frame members 11, however, said packing is broken away, as shown at 15, Fig. 3, thus permitting said frame members to bear directly against the shoulder forming one side of said rabbet 8.

With the described construction, it is obvious that the panes or plates 7 will be supported so as to be freely movable within a very limited range and that practically tight joints will be formed between the edges of adjacent plates and that rattling of said panes or plates will be prevented. Owing to their shape, also, the frame members 11 are very stiff, so that they will sustain the weight of utensils and dishes resting on the surface of the door A, when in lowered position; thus relieving the panes or plates 7 from all strain due thereto. Also, such utensils and dishes will rest directly upon the flanges of said frame members 11, which extend above the surfaces of said plates or panes 7, thus preventing contact of said

utensils and tools with the surfaces of the glass, whereby scratching of the glass will be prevented as utensils and dishes are slid into or out of the stove oven, all in the manner desired.

I claim:

1. An oven door comprising a door proper and a lining therefor, said door proper and lining being provided with corresponding openings together forming an opening through said oven door, said door proper being also provided with a rabbet around the opening therein and the edges of the door lining around the opening in said lining projecting over the rabbet in the door proper, a window comprising a plurality of relatively small panes or plates of glass secured in the opening in said oven door for closing the same, the outer edges of said panes or plates of glass extending into the space between the rabbet in said door proper and the edges of the door lining around the opening therein which project over said rabbet, the means for securing said panes or plates of glass in said opening comprising frame members which extend across said opening in said oven door between adjacent panes or plates of glass the ends of which are adapted to be clamped in the rabbet in the door proper by the projecting edges of the door lining around the opening therein and which are provided with grooves adapted to receive the edges of said panes or plates of glass, substantially as described.
2. An oven door comprising a door proper and a lining therefor, said door proper and lining being provided with corresponding openings together forming an opening through said oven door, said door proper being also provided with a rabbet around the opening therein and the edges of the door lining around the opening in said lining projecting over the rabbet in the door proper, a window comprising a plurality of relatively small panes or plates of glass secured in the opening in said oven door for closing the same, the outer edges of said panes or plates of glass extending into the space between the rabbet in said door proper and the edges of the door lining around the opening therein which project over said rabbet, said space being slightly wider than the thickness of said panes or plates of glass, the means for securing said panes or plates of glass in said opening comprising frame members which extend across said opening in said oven door between adjacent panes or plates of glass, the ends of which are adapted to be clamped in the rabbet in the door proper by the projecting edges of the door lining around the opening therein and which are provided with grooves adapted to receive the edges of said panes or plates of glass, said grooves being formed by thin metal flanges and being slightly wider than the edges of the panes or plates of glass which they are adapted to receive and being contracted at their outer ends so as to bear upon the surfaces of said panes or plates of glass with a slight frictional engagement, substantially as described.

which they are adapted to receive, substantially as described.

3. An oven door comprising a door proper and a lining therefor, said door proper and lining being provided with corresponding openings together forming an opening through said oven door, said door proper being also provided with a rabbet around the opening therein and the edges of the door lining around the opening in said lining projecting over the rabbet in the door proper, a window comprising a plurality of relatively small panes or plates of glass secured in the opening in said oven door for closing the same, the outer edges of said panes or plates of glass extending into the space between the rabbet in said door proper and the edges of the door lining around the opening therein which project over said rabbet, said space being slightly wider than the thickness of said panes or plates of glass, the means for securing said panes or plates of glass in said opening comprising frame members which extend across said opening in said oven door between adjacent panes or plates of glass, the ends of which are adapted to be clamped in the rabbet in the door proper by the projecting edges of the door lining around the opening therein and which are provided with grooves adapted to receive the edges of said panes or plates of glass, said grooves being formed by thin metal flanges and being slightly wider than the edges of the panes or plates of glass which they are adapted to receive and being contracted at their outer ends so as to bear upon the surfaces of said panes or plates of glass with a slight frictional engagement, substantially as described.
4. An oven door comprising a door proper and a lining therefor, said door proper and lining being provided with corresponding openings together forming an opening through said oven door, said door proper being also provided with a rabbet around the opening therein and the edges of the door lining around the opening in said lining projecting over the rabbet in the door proper, a window comprising a plurality of relatively small panes or plates of glass secured in the opening in said oven door for closing the same, the outer edges of said panes or plates of glass extending into the space between the rabbet in said door proper and the edges of the door lining around the opening therein which project over said rabbet, the means for securing said panes or plates of glass in said opening comprising frame members which extend across said opening in said oven door between adjacent panes or plates of glass the ends of which are adapted to be clamped in the rabbet in the door proper by the projecting edges of the door lining around the opening therein and which are provided with grooves adapted to receive the edges of said panes or plates of glass, said grooves being slightly wider than the edges of the panes or plates of glass, said grooves being formed by thin metal flanges and being slightly wider than the edges of the panes or plates of glass which they are adapted to receive and being contracted at their outer ends so as to bear upon the surfaces of said panes or plates of glass with a slight frictional engagement, substantially as described.

ed to receive the edges of said panes or plates of glass, the frame members which receive adjacent edges of adjacent panes or plates forming a substantially unitary structure, 5 substantially as described.

5. An oven door comprising a door proper and a lining therefor, said door proper and lining being provided with corresponding openings together forming an opening 10 through said oven door, said door proper being also provided with a rabbet around the opening therein and the edges of the door lining around the opening in said lining projecting over the rabbet in the door proper, a 15 window comprising a plurality of relatively small panes or plates of glass secured in the opening in said oven door for closing the same, the outer edges of said panes or plates of glass extending into the space between the 20 rabbet in said door proper and the edges of the door lining around the opening therein which project over said rabbet, the means for securing said panes or plates of glass in said opening comprising frame members 25 which extend across said opening in said oven door between adjacent panes or plates of glass the ends of which are adapted to be clamped in the rabbet in the door proper by the projecting edges of the door lining 30 around the opening therein and which are provided with grooves adapted to receive the edges of said panes or plates of glass, the frame members which receive adjacent edges of adjacent panes or plates of glass being 35 formed from an integral strip of thin sheet metal comprising connected web sections disposed with their rear surfaces in contact, means for connecting the outer ends of said web sections and outwardly projecting marginal flanges on said web sections, substantially as described.

6. An oven door comprising a door proper and a lining therefor, said door proper and lining being provided with corresponding 45 openings together forming an opening through said oven door, said door proper being also provided with a rabbet around the opening therein and the edges of the door lining around the opening in said lining projecting over the rabbet in the door proper, a 50 window comprising a plurality of relatively small panes or plates of glass secured in the opening in said oven door for closing the

same, the outer edges of said panes or plates of glass extending into the space between the 55 rabbet in said door proper and the edges of the door lining around the opening therein which project over said rabbet, the means for securing said panes or plates of glass in said opening comprising frame members 60 which extend across said opening in said oven door between adjacent panes or plates of glass the ends of which are adapted to be clamped in the rabbet in the door proper by the projecting edges of the door lining 65 around the opening therein and which are provided with grooves adapted to receive the edges of said panes or plates of glass, the frame members which receive adjacent edges of adjacent panes or plates of glass being 70 formed from an integral strip of thin sheet metal and comprising web sections connected at one end and disposed with their rear sides in contact, means for securing the opposite ends of said web sections together, comprising 75 a lip on one thereof which is bent over the other and outwardly projecting flanges at the edges of said web sections, substantially as described.

7. An oven door provided with a continuous hole or opening and with a rabbet which surrounds said hole or opening, a window comprising a plurality of relatively small panes or plates of glass for closing said opening, and means for securing said panes or 80 plates of glass in said opening, said means comprising a retaining strip secured to said door around the opening therein the edges of which overlap the outer edges of said panes or plates of glass and members which 85 extend across the opening in said door between adjacent panes or plates of glass, the ends of which are adapted to be clamped in fixed positions in the rabbet in said door by the retainer plate secured to said door and 90 which are provided with grooves adapted to receive the edges of said panes or plates, substantially as described.

In testimony, that I claim the foregoing as my invention, I affix my signature in presence of two subscribing witnesses this 30th day of April, A. D. 1909.

LEWIS MOORE.
